PATENTED APR. 24, 1906.

J. WILKINSON.

CONTROLLER MECHANISM FOR MULTIPLE STAGE TURBINES.

APPLICATION FILED JAN. 20, 1905.

UNITED STATES PATENT OFFICE.

JAMES WILKINSON, OF BIRMINGHAM, ALABAMA, ASSIGNOR TO WILKINSON TURBINE COMPANY, A CORPORATION OF ALABAMA.

CONTROLLER MECHANISM FOR MULTIPLE-STAGE TURBINES.

No. 818,499.

Specification of Letters Patent.

Patented April 24, 1906.

Application filed January 20, 1905. Serial No. 241,977.

To all whom it may concern:

Be it known that I, JAMES WILKINSON, a citizen of the United States, residing at Birmingham, in the county of Jefferson and State of Alabama, have invented new and useful Improvements in Controller Mechanism for Multiple-Stage Turbines, of which the following is a specification.

My present invention relates to controller mechanism for a multistage turbine provided with two or more independent sets of coöperating nozzles and buckets, which act to drive the turbine in reverse directions or at different speeds, or both.

It is the object of my invention to provide the stage-nozzles with independent valves which are controlled automatically by the pressure conditions within the turbine, and more particularly within the stage from which the valves act to control the exhaust.

In a pending application I have shown a direct-acting multistage turbine provided with automatic stage-pressure-controlled valves between wheel-compartments and fully described the advantages derived from their use—such as the better control of the fluid throughout its active agency within the turbine, the maintenance of stage-pressures, and the securing of a successive opening and closing of the stage-valves in correspondence with the operation of the supply-valves—whereby the proportion of the fluid's working passage across stages is maintained for all load conditions without complicating the governing mechanism. While these advantages apply generally to all types of turbines wherein the motor fluid is fractionally expanded in the reversing or two-speed turbines, such as described in my Letters Patent Nos.

752,610 and 752,496, it becomes of particular advantage, since in these turbines it is necessary to valve all the nozzles for each stage. The use of automatic stage-valves which will operate responsive to the opening and closing of the supply-valves will materially simplify the controller mechanism, which need then only control the operation of the supply-valves. The character of the controller mechanism for the supply-valves and the turbine construction does not form an important part of my present invention, the gist of which is the use of a plurality of automatic stage-valves in a turbine having independent nozzles and buckets acting with different

driving effects, and I desire to claim this broadly herein.

More particularly, my invention comprises the details of construction and arrangement of parts hereinafter more fully described, and illustrated in the accompanying drawings, in which—

Figure 1 represents a vertical sectional view taken through a two-stage turbine designed to reverse at half-speed and showing in similar sectional view one of the compound controller-casings for the stage-valves. Fig. 2 is a vertical sectional view taken through both working passages for the motor fluid and showing the reverse disposition of the nozzle-passages and the bucket-wheel construction. Fig. 3 is a detail view of the valve-motor, taken along the line *xx*, Fig. 1. Fig. 4 represents a series of controller-pistons for a row of stage-valves and illustrates their successively decreasing size for the purpose of producing a successive action of the stage-valves under their control as the pressure in the controlling stage varies. Fig. 5 is a detail view of one of the controller piston-valves.

Similar reference-numerals refer to the same parts throughout the drawings.

As illustrated, the turbine comprises the supply-head 1, exhaust-head 2, and any desired number of interposed diaphragm-partitions 3, (only one being shown,) which are held in position by an outer shell or jacket 4. The diaphragm shown divides the turbine into two stages, within each of which is disposed a bucket-wheel 5, provided with a row of direct buckets 6 and a set of reversing buckets 7, arranged in two parallel rows and jointed or suitably connected to the direct buckets. Stationary intermediates 8 are disposed between each double row of reversing-buckets 7, being locked in position between a retaining-ring 9 and a shoulder 10 of the supply-head.

The head 1 has two sets of reversely-disposed nozzles 11 and 12, which respectively discharge motor fluid at an angle against buckets 6 and 7. Fluid-pressure may be supplied to these nozzles through pipes leading from any suitable source and threaded into the threaded inlet ends of the nozzles. Any desired number of supply-nozzles may be used, and they may be arranged in any desired manner and the flow of motor fluid therethrough controlled by a governor or by

hand with or without the interposition of a relay power for actuating valves, such as 13 and 14, which act to open or close the nozzles 11 and 12, respectively. Since, however, the 5 sets of nozzles 11 and 12 will act with different driving effect upon the bucket-wheels, fluid-pressure should be admitted to the turbine through but one set of corresponding nozzles at the same time.

10 A controller mechanism, such as shown and described in a pending application, Serial No. 172,588, may be used to operate the supply-valves for each set of nozzles by admitting fluid-pressure to one side or the other of the 15 wing-pistons 15, carried by stems 16, connected to the valves 13 and 14, or any of the controller mechanisms described in my Letters Patent aforesaid may be readily adapted to control both sets of supply-valves, 20 maintaining one set closed while successively opening or closing the nozzles of the other set. Inasmuch as the controller means for the supply-valves does not form an essential part of my present invention, the detailed description 25 will be limited to the means for automatically controlling the flow of motor fluid through the stages.

Two sets of stage-nozzles 17 and 18, preferably corresponding in number with the 30 supply-nozzles, lead through each diaphragm 3 and coöperate, respectively, with the buckets 6 and 7 on the wheel in the succeeding stage. As seen in Fig. 2, these stage-nozzles are enlarged to make provision for the expanded condition of the motor fluid and are arranged slightly in advance of their corresponding supply-nozzles or so as to form series or rows of nozzles across stages through which the motor fluid flows in streams, which 35 practically maintain their identity. It is my purpose to vary the volume of motor fluid in accordance with the load by cutting on or off the streams across stages. To effect this, I provide each direct stage-nozzle 40 45 17 with a rotary valve 19 and each reversing-nozzle 18 with a rotary valve 20, which valves are similar to valves 6 and are seated in the diaphragms 3. The stage-valves are preferably operated by wing-pistons 15, seats 21 50 for which are disposed in the valve-recess in the diaphragm. The direct and reversing nozzles are preferably so arranged in the diaphragms that a valve for one of each of these nozzles may be disposed within a common 55 seat. A passage 22, which communicates with the stage-pressure above the diaphragm, admits this pressure between the abutting ends of the pair of valves 19 and 20 in each seat. To simplify construction, passage 22 60 is common to the several pairs of valves and has but one point of communication (not here shown) with the stage above the diaphragm.

The automatic controller mechanism for

the stage-valves comprises a compound controller-casing 23 for each pair of stage-valves 19 and 20, this casing being shown disposed without the jacket 4 and communicating by pipes 24 and 25 with two passages 26 and 27, Fig. 3, leading through the shell and diaphragm to each side of the wing-piston for a direct valve 19. Two pipes 28 and 29 connect with passages also leading through the shell and diaphragm to each side of the wing-piston for a reversing-valve 20.

The main body portion 30 of the casing is formed with two high-pressure cylinders 31 and 32, leading inwardly from each end of the casing and communicating through a reduced passage 33 at their inner ends. A pipe 34 enters the passage 33 and admits a high pressure to the inner beveled ends of the cylinders. A cap 35 is shrunk or otherwise secured to each end of the casing 30 and forms the low-pressure cylinders 36 and 37 for the differential piston-valves 38 and 39, whose high-pressure heads 40 move within the cylinders 31 32, while their low-pressure heads 41 move within the cylinders 36 37, which communicate through pipes 42 43 with a three-way valve-casing 44, which in turn 45 communicates through a conduit 45 with the stage above the diaphragm within which are seated the valves under the control of the cylinder described. A rotary valve 46 within this casing acts to throw one of the pipes 42 43 into communication with the stage-pressure, while exposing the other to the atmosphere or an exhaust-pressure through a port 48. The pipes 42 43 enter the outer beveled ends of the low-pressure cylinders 36 37, which at their inner ends are exposed to the atmosphere or an exhaust-pressure through a passage 49, leading through the casing 30 and opening into a pipe 50. The high-pressure heads of the pistons are reduced at two points to form annular chambers 51 and 52, the latter of which is exposed to high pressure through a passage 53, leading through the high-pressure head of the piston, while the former chamber 52 is exposed to exhaust-pressure through a passage 54, leading through the piston-stems and constantly open to the exhaust-pressure existing at the inner ends of the low-pressure cylinders. It 55 will be noted that each pair of pipes 24 25 and 28 29 enter their respective cylinders at points so spaced that as their controlling-pistons move from one to the other of their operating positions each pipe will be alternately exposed to a high or exhaust pressure. Thus, as shown, pipes 28 and 29 register with the chambers 51 and 52, and therefore with exhaust and high pressures, respectively, while pipe 25 registers with the low-pressure chamber 51 and pipe 24 opens into the high-pressure chamber. The pistons and their cylinders are beveled to cause the former to move

full stroke without assuming intermediate operating positions.

It being understood that a controller-casing 23 is provided for each pair of stage-valves the control of stage-valves will be automatically effected in the following manner: Assuming that it is desired to cause the turbine to reverse, the valve or valves 46 will be moved to the position shown in Fig. 1, when the low-pressure cylinders 36 will be exposed to the atmosphere or exhaust through pipe 42 and port 48, and the high pressure acting against their heads 40 will move the valves to the position shown and flowing through pipes 24 and passages 27 will move the wing-pistons 15 to cause valves 19 to close the nozzles 17. All of the pistons 38 being moved to this position all of the stage-valves 19 will be closed, and consequently no fluid-pressure can flow through the direct nozzles. The movement of the valves or valves 46 to the position described throws all the low-pressure cylinders 37 into communication with the first stage-pressure through pipes 43 and 45, which pressure thus acts against the heads 41 of the pistons 39 in opposition to the high pressure acting against the heads 40 of said pistons. The heads of these pistons are given any desired differential, according to the pressure which is to be maintained in the stage which they control. Before the supply-valves 14 have been opened to admit pressure to the first stage the high pressure acting against heads 40 of the pistons 39 will move them all to their lowered position and will act to close all of the valves 20. As the supply-valves 14 are opened and the pressure rises in the first stage the pressure increases below the piston-heads 41 until in the case of the piston having the largest differential this stage-pressure will overcome the high pressure and move the piston 39 to the position shown in Fig. 1. This movement of the piston reverses the pressure in pipes 28 and 29 and opens a valve 20. If the pressure in said stage continues to increase, the other valves 39, according to their relative differentials, will successively be moved by the stage-pressure to open other valves 20. In Fig. 4 I have illustrated a part of a series of the piston-valves 38, showing the difference in area of their low-pressure heads, by means of which I give them the varying differential designed to produce the successive operation of the stage-valves. This differential may be produced in any other desired manner. As the stage-pressure lowers the high pressure will successively overcome the stage-pressure and move pistons 39 to close the valves. It is my purpose to so proportion the several controller-pistons for the stage-valves that they will all operate within a very small variation of stage-pressure—say from two to four pounds per square inch—

and also so that the opening or closing of a supply-valve will cause a variation in stage-pressure which will effect the opening or closing of a corresponding stage-valve.

It is my purpose to arrange the controller-casing 23 together and dispose them so that a compound valve 46 instead of a plurality of separate valves may be used to simultaneously expose cylinders 37 or 38 to the stage-pressure. When it is desired to reverse the turbine and cause it to drive forward, it is only necessary to move the valve 46, so that it admits the stage-pressure to the cylinders 36 and exposes the cylinders 37 to an exhaust-pressure. This will cause the valves 20 to close the stage-nozzles 18, while the pistons 38 control the opening and closing of the direct valves 19.

Though I have shown my invention applied to a two-stage turbine, its advantages are even greater in turbines having a larger number of stages, for, if desired, by means of branch passages communicating with the controller-pipes 24, 25 and 28, 29 each compound controller-casing 23 may automatically control the opening and closing of a corresponding row of valves across stages. If desired, a separate controller-casing could be used for each pair of valves for each stage and the controller-pistons so designed as to produce the same cross-stage control of the valves.

Though the details of construction of the controller-casing are considered a preferred means for controlling the automatic operation of the stage-valves, I do not desire to limit myself to the same nor to the construction of the nozzle-valves and motors, as it is my purpose to claim, broadly, first, a number of independently-controlled automatic stage-valves for a reversing or two-speed turbine, and, second, the provision of a plurality of automatic controller-valves utilizing a relay power, such as fluid-pressure, to control the operation of stage-valves in a reversing or two-speed turbine. For the purposes of my invention it is immaterial whether the stages be inclosed within the same shell or formed in separate shells or whether the turbine be adapted to operate in series with other turbines or reciprocating engines.

Where the casings 23 control valves for the low-pressure stages, atmosphere may be admitted through pipe 34 instead of a high pressure and port 48 connected with the exhaust or condenser. If desired, each valve 38 or 39 may control two or more corresponding stage-valves. My invention contemplates the adaptation of each of these valves to control all the corresponding valves of a stage, which may be of advantage where the whole supply of fluid to the turbine is pulsated, as in the manner described in my Letters Patent No. 766,921.

Having thus described my invention, what I claim as new, and desire to protect by Letters Patent, is—

1. In a turbine, a wheel-compartment, a rotatable element therein, nozzles to discharge motor fluid with different driving effects upon said element, means to maintain the nozzles acting with one driving effect closed, and means comprising a plurality of valves independently and automatically controlled by pressure conditions in the turbine to govern the flow of fluid through the active nozzles.
2. In a turbine wherein the motor fluid is expanded in stages and discharged against rotatable elements, two or more sets of conduits between two stages, valves for said conduits adapted to be automatically and independently controlled by internal pressure, and means to maintain one set of conduits closed while the flow of motor fluid through the other set is automatically regulated.
3. In a reversible multiple-stage turbine, a set of direct stage-nozzles, a set of reversing stage-nozzles, valves for each set of nozzles adapted to be automatically and independently controlled by internal-pressure conditions, in combination with means to prevent the flow of motor fluid through both sets of passages at the same time.
4. In a reversible multiple-stage turbine, a number of direct and reversing stage-nozzles, a valve for each nozzle which is adapted to be automatically and independently controlled by internal pressure, and means to subject the valves of but one set of nozzles at a time to the control of the internal pressure.
5. In a reversible multiple-stage turbine, a plurality of direct and reversing stage-nozzles, means to maintain the reversing-nozzles closed when the turbine is driven forward, and a number of automatic valves, governed by internal-pressure conditions, which control means for successively opening or closing the direct nozzles.
6. In a reversible multiple-stage turbine, a plurality of direct and reversing nozzles, means to maintain the direct nozzles closed when the turbine is being driven in a reverse direction, and a number of automatic valves, governed by internal-pressure conditions, which control means for successively opening or closing the reversing-nozzles.
7. In a two-speed turbine, independent working passages for producing different speeds of rotation, and automatic stage-pressure-controlled valves for regulating the flow of motor fluid in said working passages between stages.
8. In a multiple-stage turbine having two independent sets of working passages, one acting to drive the turbine forward, and the other producing a different driving action as to speed or direction, a separate automatic stage-pressure-controlled valve for controlling the flow of motor fluid through each passage between stages, and means to cut one set of working passages out of service.
9. In a multiple-stage turbine, two conduits between stages which discharge motor fluid with different driving effects against a bucket element in the stage of lower pressure, valves automatically operated by the pressure in the higher-pressure stage for controlling the flow of motor fluid through each of said nozzles, and means to expose but one of said valves at a time to said controlling stage-pressure.
10. In a multiple-stage turbine, two sets of conduits between stages which discharge fluid-pressure with different driving effects against a bucket element, valves for said conduits, and a number of controller devices automatically acted upon by internal pressure, each device controlling, by fluid-pressure means, valves for a conduit in each set.
11. In a multiple-stage turbine, two sets of supply and stage nozzle passages which co-operate with sets of rotatable buckets and act to discharge fluid-pressure with different driving effects against the bucket-bearing elements, a number of separate fluid-actuated valves for each set of stage-nozzles, a number of stage-pressure-controlled automatic controller-valves for the valves of each set of stage-nozzles, and means to maintain one set of stage-nozzles closed while the controller-valves for the other set successively open or close the same.
12. In a multiple-stage turbine, a plurality of sets of nozzle-passages between stages which discharge fluid-pressure with different driving effects against a bucket element, a fluid-pressure-actuated valve for each nozzle, a controller-casing, automatic valve means therein exposed to a substantially constant force which is opposed by internal turbine-pressure supplied to said casing, conduits leading from said casing to a valve for each set of nozzle-passages, and serving to conduct a high or low pressure under the control of said automatic valve means to open or close the valves.
13. In a turbine operating by stage expansion, bucket-wheels having two sets of buckets disposed at different distances from their centers, independent sets of nozzles co-operating with said sets of buckets, and a number of valves for each set of nozzles, in combination with a plurality of automatic controller-valves, which operate sensitive to stage-pressure, for each set of stage-valves, and means to maintain one set of said controller-valves inactive.
14. In a multiple-stage turbine, a number of controller-casings for stage-valves comprising each two differential cylinders, piston-valves in said cylinders, conduits leading from the low-pressure ends of said cylinders to the interior of the turbine, ports admitting

high pressure to the high-pressure ends of said cylinders, passages leading from each cylinder to a group of stage-valves, and means to expose a corresponding low-pressure cylinder of each casing to the turbine-pressure while exposing the other low-pressure cylinders to the atmosphere or exhaust-pressure.

15. In a multiple-stage turbine, a controller-casing for stage-valves comprising a main body portion, and a cap secured to each end thereof, said casing comprising two differential cylinders whose low-pressure ends are formed in said caps, and whose high-pressure ends are formed in said body portion, ports admitting high pressure to one end of said cylinders, and conduits leading from their other ends to a valve-casing which communicates through one port with an exhaust or atmospheric pressure, and through the other with a stage-compartment in the turbine, and a valve in said casing which maintains one of said conduits in communication with the stage-pressure and the other 25 with the low pressure or atmosphere, and means under the control of said automatic valves to operate stage-valves.

16. In a multiple-stage turbine, a stage-pressure-actuated controller device for stage-valves comprising a compound differential cylinder, automatic controller-valves in said cylinder, ports adapted to admit high and exhaust pressures to opposite ends of said valves, and conduits acting to conduct pressure under the control of said valves to operate stage-valves.

17. In a multiple-stage turbine, sets of stage-nozzles which discharge fluid-pressure with different driving effects against a bucket element, valves for each set of nozzles, and a plurality of controller devices each comprising a casing having two differential cylinders, differential piston-valves of relatively vary-

ing proportions therein exposed to a substantially constant pressure and a stage-45 pressure, and conduits to conduct a high or exhaust pressure under the control of said piston-valves to successively open or close said stage-valves, substantially as described.

18. In a multiple-stage turbine having independent working passages producing different driving effects upon bucket elements, a number of valves to control the flow of fluid-pressure between stages for each set of working passages, a number of controller-valve casings for said stage-valves, passages leading from each casing to a stage-valve for each set of working passages, and a number of automatic valves in each casing which are moved sensitive to stage-pressure and control the admission of an actuating-pressure to the valves which they control to open or close the same, and means to cause the corresponding automatic valves of each casing to be alternately controlled by stage-pressure or moved to a position where they cause the closure of the stage-valves under their control.

19. In a turbine having two independent working passages, rotatable parts acted upon by the fluid in said passages, the fluid in one passage acting to drive said parts forward and in the other passage to produce a different driving effect, separate valve means for said passages automatically responsive to internal pressure conditions and adapted to control the flow of motor fluid through each passage at an intermediate point thereof, and means to cut all said passages out of service.

In testimony whereof I have hereunto set 80 my hand in presence of two subscribing witnesses.

JAMES WILKINSON.
